UNITED STATES PATENT OFFICE.

JOHN W. NASMITH, OF HEATON MERSEY, ENGLAND.

STITCHING-MACHINE.

1,346,415.

Specification of Letters Patent. Patented July 13, 1920.

Application filed December 20, 1918. Serial No. 267,623.

To all whom it may concern:

Be it known that I, JOHN WILLIAM NASMITH, of Heaton Mersey, in the county of Lancaster, England, have invented certain 5 new and useful Improvements in Stitching-Machines, of which the following is a specification.

The present invention relates to improvements in wire stitching machines and the 10 like for stitching cardboard or wooden boxes, papers, pamphlets, etc., with wire and will be fully described with reference to the accompanying drawings in which Figure 1 is a side elevation of a machine constructed 15 in accordance with this invention and Fig. 2 is a partial end elevation. Fig. 3 is a front elevation of a cross stitcher and Figs. 4 and 5 are enlarged sectional views of the forming and driving parts.

20 It is desirable that wire stitching machines should be so constructed that material varying in thickness from a thin paper to an inch or more may be stitched. In order that this may be possible it is necessary, firstly that the space between the block 25 or anvil on which the material is placed and the end of the stroke of the ram or driver of the staple can be quickly altered to suit and secondly, that the length of wire fed 30 and cut off to form the staple can be quickly altered so that the legs of the staple when formed may be of sufficient length to suit the thickness of the material with the necessary surplus for clenching.

35 Machines have been constructed in which a small variation in the length of leg is possible by a simple adjustment but in machines where a large variation is required the anvil or block is first adjusted to suit 40 the thickness of material to be stitched and then an independent adjustment adds or subtracts a fixed amount to each leg, $\frac{1}{2}$ " for example, which may not be in strict proper relation to the change in thickness of material, being either too much or too little to 45 make a satisfactory clench.

Next when the ram has completely driven the staple and is pressing down upon it, it is desirable that it should dwell there for an 50 instant while the clenching is done. This has been done in the case of treadle machines in which the ram is operated by a cam but in power machines the ram or staple driver is operated by a crank, and finally, in such 55 machines the staple-wire feed is conven-

iently made while the previously formed staple is being driven. For this purpose the wire is pushed through a notch in the end of the loop-bar, the end of which is closed by the staple former and driver passing across 60 it. When the staple former and driver are raised after completing their stroke, the loop-bar containing the cut-off length of wire to form the next staple is pushed in to be ready in position under the former 65 which will bend the legs on its stroke. Various forms of gripper are in use to prevent the wire from falling out of the notch in the loop-bar when the former and driver are raised and leave the notch exposed and 70 they require special operative mechanism to put them in and out of action. I desire to combine a simple gripper with the "frog" supporting the legs of the staple while it is being driven, which requires no special 75 mechanism to operate it, and is pushed aside by the driver itself as it descends.

The object of my invention is therefore to provide means whereby the displacement of the anvil automatically and simultaneously 80 adjusts the feed and cut-off in exact proportion so that the surplus allowed in the construction of the machine for the purpose of clenching remains always the fixed and proper amount. I also provide means 85 to cause the driver driven by a crank, to dwell while clenching takes place and to provide a simple gripper combined with the frog that requires no operative parts.

In carrying my invention into effect I 90 mount the anvil A, Fig. 1, firmly in a block or carrier B which is provided with a tongue B² on the back fitting accurately between planed vertical ribs R cast on the frame F of the machine. A bolt 1 passes through a 95 vertical slot 1^a in the frame F and through a hole in the block or carrier B and anvil A and is provided with a screwed clamping handle H whereby the carrier and anvil can be firmly secured to the ribs R. To facilitate the displacement of the anvil when the bolt is slackened, the handle L is provided. It pivots freely on the fixed stud 2 and has fixed in it a pin 3 which engages in a notch or slot 3^a formed in the anvil. 100

The carrier B is formed with a prolongation B' which slides accurately between two further ribs R' cast upon the framing F. The prolongation B' has accurately formed 110 on its face in suitable position a projecting

bead I inclined at 45° to the vertical. This bead or incline I engages in a corresponding groove in the back of the bar or slide 4 which is let into corresponding grooves formed horizontally in the ribs R' and a plate E keeps the slide 4 in the grooves while leaving it free to slide horizontally when B is raised or lowered. The screwed end of the slide 4 is secured to a bracket T which is in turn pinned to the plate P. This plate P has fixed on its front face the cut off knife carrier K' and its knife K which are of the ordinary kind and need not be further described except to note that the knife and its carrier participate in any displacement of the plate P. The fixed line QQ represents the center of the staple when formed. The plate P has a tongue formed on the back which fits accordingly in a horizontal groove in the finished face 5 cast on the frame F in which is also the slot X through which passes the clamping screw 6 whereby the plate P is secured to the face 5.

25 The feed gripper G is of the ordinary kind and need not be described in detail and may be replaced by the ordinary wheel and ratchet. It receives a horizontal to and fro movement through the link 7 from the lever V rocking on the fixed pivot 8 under the influence of the cam M. When moved to the left it grips and feeds the wire, when moved toward the right it slides along the wire without moving it.

35 The upper part of the lever V is precisely half the length of the lower or pendant part. Exactly midway in the lower part is the steel point O which comes and rests against a set screw or stop 9 carried in the bracket T. The cam M has its face formed so as to give the maximum feed required. When only the minimum feed is required the roller W at the extremity of the upper part of the lever V only touches the highest part of the cam M since it cannot follow it further than allowed by the stop 9. The cam M is keyed upon the revolving driving shaft S receiving its motion from a driving pulley through a one revolution clutch in the ordinary way.

40 Fig. 1 shows the parts in position to give the minimum feed and shortest staple and the cut-off knife K in its nearest position to the center line QQ of the staple. If now the clamping screw 1 and the handle H be loosened, the anvil can be lowered to increase the distance Z to accommodate a thicker material. (It will be understood that a considerable space is required here to insert the thinnest material and turn a box rapidly without withdrawing it from the anvil, the end of the staple former and driver in performing their stroke traversing this distance to come down on the material on the anvil.) But by means of the incline I, the 45 bar 4, bracket T and screw 9 and the plate

P with the knife K, are all drawn to the right an exactly similar amount so that the knife K cuts off the wire so much farther from the center line QQ of the staple and provides the necessary addition to the right 70 leg of the staple. But the left leg must also be lengthened by a similar amount and to do this the lower extremity of the lever V is drawn by the spring 10 double the distance that the screw 9 has moved and brings the 75 roller W nearer the face of the cam M, causing a greater amount of the throw of the cam M to come into operation, the feed being thus increased by double the amount that the anvil has been lowered so as to supply the exact addition to each leg of the staple. Similarly the reverse operation shortens the legs and the cut-off.

80 In place of the incline I, levers may be used to connect the block B to the cut off plate P and the feed regulating bracket T, as shown in Fig. 3 which is an application to a machine in which the staple is across instead of lengthwise of the anvil. The shaft 11 has pinned on its forward end a lever 12 90 the lower end of which is forked to engage with a pin 13 which serves also as the clamping screw for the plate P. On the other end of the shaft 11 is pinned a second lever 14 at right angles to the lever 12. At its free 95 end it carries a pin 15 engaging in a slot 16 in a bracket 17 fixed on the projection B' of the anvil block B. In this arrangement lever V is in two parts V and V' Fig. 3, the upper part V' being rocked by an eccentric 100 W in place of a cam and the pivot 8 is carried on an arm 37 cast on the head 28. The upper lever V' with the set screw V³ in its lower limb V⁴ always rocks the full throw of the eccentric to give the maximum feed. The 105 lower lever V can only follow under the influence of its spring 10 as far as the screw 9 allows. The set screw V³ then ceases to contact with V and continues to move to the right. From this it will be seen that the 110 raising or lowering of the anvil block B produces a corresponding displacement of the plate P with its knife K and feed regulation bracket T, altering the feed and cut-off as already described.

115 In Figs. 1, 2 and 3 the cam C is shown in its position when the machine is at rest. 18 is a pin fixed in the face of the cam C and has on its outer face a roller 19 running in the slot of the part 20 which is firmly attached by the screws 21 to the staple driver 22. As the cam C revolves the driver is lowered and raised and in order that it may have a momentary dwell when at the bottom a shallow depression 23 is formed in the lower 125 face of the slot in part 20. This depression is an arc of a circle having the same radius as the circle described by the pin 18 in the face of the cam. The driver is at the bottom of its stroke when the roller 19 enters the 130

depression and is held there till the bowl has traversed the depression, during which time the clench has been made.

The frog 24 (Figs. 2, 4 and 5) is firmly secured to a pendant 25 which is hinged on a pin 26 in a plate 27^a formed on the top of the plunger 27 and fitting between the forked upper end 25^a of the pendant 25. The plunger passes freely through a hole drilled in the head 28. On its lower end is a washer 29 which limits the upward movement under the influence of the spring 30. One member of the forked end 25^a of the pendant 25 passes on either side of the staple former 31 and their outer ends are connected by the pin 32 against which rests the fixed spring 30. The effect of this spring is to keep the pendant always against the stop washer 29 except when carried down by the projection 31^a on the former 31 coming on the plate 27^a on the plunger 27. It also keeps the frog constantly in the forked lower end of the former till pushed aside by the driver as it drives the staple.

25 A narrow slit or groove 24^a Fig. 4 is formed in the middle of the frog 24 in which lies a steel blade 33 pivoted at 34 and pushed constantly forward by the spring 35 (Figs. 4 and 5). In Fig. 4 the parts are seen in position when the machine is at rest and the cut off length of wire 36 (the end of which only is seen) is in position so that when the former 31 descends the wire will be bent on each side of the loop bar 38 into the 35 staple former and held by the gripper 33 in the nick in the loop bar 38.

Fig. 5 shows the parts in the positions they occupy when the feed is just finished and the wire has been cut off. The rising former 31 and driver 22 cover the end of the loop bar 38 so that the cut off length of wire cannot fall out and the driver is provided in its lower end with a narrow slit through which the gripper 33 is pushed by 45 the spring 35 before the driver has passed off the end of the loop bar 38. As soon as this takes place the loop bar under the influence of its stronger spring 39 is pushed to its initial position carrying the gripper back 50 with it, since spring 35 is only weak compared with 39. The wire is therefore constantly held after being cut off and cannot fall out of the loop bar and no special parts are required to operate the gripper.

55 It will be seen that the anvil is adjustable in a predetermined path, and that the path of the reciprocating knife K of the wire-cutting mechanism is adjustable in a direction substantially at right angles with the path in which the anvil is adjustable. It will also be seen that connections are provided between the anvil, the cutting mechanism and the feeding mechanism (which includes a gripper and gripper-reciprocating means,) said connections being actuated by

a given adjustment of the anvil to cause an equal adjustment of the path of the knife, and a proportional increase or decrease of the length of travel of the said gripper, the construction and arrangement being as described, so that any adjustment of the anvil causes the formation of staple legs of equal length in proportion to the adjustment of the anvil.

Claims:—

1. A wire stitching machine comprising an anvil adjustable in a predetermined path, means for positively securing the anvil at any point to which it is adjustable, a wire feeding mechanism including a wire gripper adapted to alternately feed and release the wire, gripper reciprocating means comprising a cam, and a two-armed lever having arms of unequal length, the longer arm being connected with the wire gripper and the shorter arm being in the path of said cam, a wire-cutting mechanism including a reciprocating knife-carrier having a knife adapted to cut the wire fed by the feeding mechanism, the path of said knife-carrier being adjustable in a direction substantially at right angles with the path in which the anvil is adjustable, and connections between the anvil, the knife-carrier and the gripper-reciprocating means, actuated by a given adjustment of the anvil to cause and maintain an equal adjustment of the path of the knife-carrier and to cause and maintain a proportional increase or decrease in the length of travel of the gripper, the said connections including an anvil carrier movable in fixed guides, and a slide movable in a path at right angles with the path of the anvil carrier, means being provided for causing the anvil, when moved, to adjust 105 the slide an equal amount, and a stop also connected with and movable by the slide and arranged to limit the movement of the shorter lever arm toward said cam, the construction and arrangement being such that any adjustment of the anvil causes the formation of staple legs of equal length proportioned to the adjustment of the anvil.

2. A wire-stitching machine substantially as specified by claim 1, including a frog, a pivoted spring-pressed wire gripper in the frog, a driver having a slotted end, and a grooved loop bar, the arrangement being such that when the driver rises the gripper passes through the slit in the driver and holds the wire in the loop bar before the driver uncovers the wire groove in the loop bar.

In testimony whereof I have affixed my signature, in presence of two witnesses.

J. W. NASMITH.
